ROLLING MILL

George H. Rose, Cleveland Heights, Ohio

Application February 6, 1934, Serial No. 709,992

3 Claims.

(Cl. 80—56)

This invention relates to improvements in rolling mills, and more particularly to a spring separator for rolling mill chocks.

One object of the present invention is the provision of a novel elongated spring separator for rolling mill chocks which enables the use of antifriction bearings for the necks of the rolls of a mill.

Another object is the provision of a novel device of the class described which will be cheap and easy to manufacture and will require no adjustment or replacement while in service.

These and further objects will be apparent after referring to the drawings, in which:

15 Figure 1 is a side elevation of a conventional type of 2-high mill which has been adapted to employ the device of the invention.

Figure 2 is an enlarged fragmentary sectional elevation of the mill of Figure 1.

20 Figure 3 is a fragmentary front elevation, partly in section, of the mill of Figures 1 and 2.

Figure 4 is a perspective view of the novel spring separator of the invention.

Referring more particularly to the drawings, 25 the numeral 2 designates a housing for supporting the rolls of any of the well known types of rolling mill.

The housing 2 supports on both of its sides a pair of chocks 3 in vertical juxtaposition, and 30 which are adapted for vertical movement with respect thereto. A plurality of clips 4 are secured to the housing 2 by means of bolts 5 for maintaining the chocks 3 from moving sidewise with respect to the housing.

35 A bearing 6 is mounted in each of the chocks 3 and are shown in the drawings as being of the "roller type", although it is to be understood that any well known antifriction bearing may be used.

The rolls 7 of the mill are mounted in the 40 housing 2 by way of having their necks 8 journaled in the bearings 6.

In accordance with well known principles, a screw 9 is provided for moving the upper of the chocks 3 by means of a hand-lever 10, and the 45 bottom of the chocks 3 are moved vertically by means of the usual wedge-adjuster, generally indicated at 11.

The adjoining edges of adjacent pairs of chocks 3 are each provided with convexed mid-portions 12, intermediate flat portions occupying a common plane at right angles to the vertical center line of the housing 2, and a concavity adjacent each of its ends.

50 The novel elongated spring separator for resiliently maintaining the chocks 3 apart is generally

indicated at 15 and is provided on its upper and lower mid-portions with a concavity 16 conforming closely to the convexed mid-portions of the adjoining edges of the chocks. The intermediate portions of the elongated spring separator 15 are provided with flat surfaces 17 conforming substantially to the intermediate surfaces of the chocks while the extremities thereof are each provided with an upper and lower convexed portion 18 conforming closely to the concavities 14 10 of the chocks and cantilevered from the main or mid-portion of the separator 15, thus leaving a slot 19 between the upper and lower convexed portions 18 to allow for spring deflection when the mill rolls and chocks are brought closer together. 15

In installation, the lower of the chocks 3 on either side of the mill are disposed in the housing 2 and each provided with a spring separator 15. Each of the upper chocks 3 is positioned in the 20 mill and in contact with the upper sides of the ends of the spring separator.

Due to the elasticity of the cantilevered ends of the spring separator 15 the convexed portions 18 are held in contact with the corresponding 25 concavities adjacent the ends of the chocks, while the mid-portions of the separator 15, having a contour generally similar to the adjacent surfaces of the chocks, are maintained in spaced relation thereto, so that the only contact between the 30 separator and chocks is at the ends 18. The space or clearance between the aforesaid surfaces must be less than the maximum allowable deflection of the cantilevered ends 18 of the separator 15. 35

As the screw 9 and wedge adjuster generally indicated at 11 are adjusted, the various chocks will be moved relative to each other and resiliency established between them at points adjacent their ends. This relationship is maintained, of course, until such adjustment is made as will cause the 40 rolls to be brought to the desired position. The roll collars will be in contact before the chocks come in contact with the mid-portions of the spring separator 15, and of course before it has reached its elastic limit. 45

Due to the convexed mid-portions 12 of the chocks 3, a sufficient cross-section of metal is permitted at the centers thereof to permit the use of roller bearings, which are recognized as being decidedly superior over the usual brass type 50 of bearing, while a resilient influence is exerted by the spring separator to maintain the chocks 3 and accordingly the bodies of the rolls 7 out of contact. There are, however, many mills employing the usual brass type of bearing which 55

render very satisfactory service, and the device of the invention may be easily adapted thereto.

While I have shown and described one specific embodiment of my invention, it will be understood that I do not wish to be limited exactly thereto, since various modifications may be made without departing from the scope of my invention, as defined in the following claims.

I claim:

- 10 1. A spring mounting for heavy elements normally free and tending to move toward each other comprising, in combination, a pair of opposed blocks for supporting said elements, the adjoining edge of each of said pair of opposed blocks having a concavity adjacent each of its ends, and a spring separator adapted to be placed between the adjoining edges of said blocks and having upper and lower cantilevered convexed portions at each of its ends conforming substantially to the concavities therein, said spring separator being disposed in such manner as to cause the upper and lower cantilevered convexed portions at each of its ends to occupy the concavities of said pair of opposed blocks while the remainder 15 of the spring separator and the remainder of the adjoining edges of said blocks are maintained in spaced relationship with respect to each other.
- 20 2. A spring mounting for heavy elements normally free and tending to move toward each other, comprising, in combination, a pair of opposed blocks for supporting said elements, the adjoining edge of each of said pair of opposed blocks having a concavity adjacent each of its ends, the mid-portion of the adjoining edge of each of said pair of blocks having a convexity and a spring separator adapted to be placed be-
- 25
- 30
- 35

tween the adjoining edges of said blocks and having upper and lower cantilevered convexed portions at each of its ends conforming substantially to the concavities therein, said spring separator being disposed in such manner as to cause the upper and lower cantilevered convexed portions at each of its ends to occupy the concavities of said pair of opposed blocks, the mid-portion of said spring separator having a concavity on each of its sides to conform substantially to the convexities of the mid-portions of the adjoining edges of said pair of opposed blocks, thus providing for close adjacency of the blocks and spring separator and the maintenance of a spaced relationship therebetween except for the end-portions thereof. 15

3. A spring mounting for mill rolls which are normally free and tending to move toward each other comprising, in combination, a pair of opposed blocks for supporting said rolls, the adjoining edge of each of said pair of opposed blocks having a concavity adjacent each of its ends, and a spring separator adapted to be placed between the adjoining edges of said blocks and having upper and lower cantilevered convexed portions at each of its ends conforming substantially to the concavities therein, said spring separator being disposed in such manner as to cause the upper and lower cantilevered convexed portions at each of its ends to occupy the concavities of said pair of opposed blocks while the remainder of the 20 spring separator and the remainder of the adjoining edges of said blocks are maintained in spaced relationship with respect to each other. 25

GEORGE H. ROSE.
